UNITED STATES PATENT OFFICE.

R. LESTER BARNEY, OF SWANTON, VERMONT.

STONE-SAWING MACHINE.

SPECIFICATION forming part of Letters Patent No. 313,643, dated March 10, 1885.

Application filed August 14, 1884. (No model.)

To all whom it may concern:

Be it known that I, R. LESTER BARNEY, of Swanton, in the county of Franklin and State of Vermont, have invented a new and Improved Stone-Sawing Machine, of which the following is a full, clear, and exact description.

The object of my invention is to provide a new and improved machine for sawing marble or other stone, which machine is simple in construction, and is provided with devices for automatically feeding the required quantities of sand and water.

The invention consists in the combination, with a saw-frame, of a suitable base for supporting the stone, a tank for receiving sand and water, a bucket-chain for raising the sand and water, and a gutter for conducting sand and water that has been dumped into it from the bucket-chain to the block of stone being sawed. A tank is also provided, from which a pipe extends downward, by means of which the sand remaining in the buckets is washed out.

The invention also consists in various parts and details, and combinations of the same, as will be fully described and set forth herein-after.

Reference is to be had to the accompanying drawings, forming part of this specification, in which similar letters of reference indicate corresponding parts in all the figures.

Figure 1 is a side elevation of my improved stone-sawing machine, parts being shown in section. Fig. 2 is a side view of the bucket. Fig. 3 is a rear view of the same. Fig. 4 is a longitudinal sectional elevation of the base and inclined platform. Fig. 5 is a cross-sectional elevation of the same, on the line $\alpha-\alpha$. Fig. 6 is a rear view of a bucket of different construction. Fig. 7 is a side view of the same. Fig. 8 is a longitudinal elevation of the faucet for drawing off the sand and water. Fig. 9 is an end view of the same.

The saw-frame A is hung in the usual manner to reciprocate in the horizontal plane, and is connected with a pitman, B, for operating it. The block of stone, C, to be sawed rests upon a suitable base, D, which in turn rests upon an inclined platform, D', on which a water-tube, E, is arranged, which is provided with branch pipes E', for delivering jets of water upon the inclined platform, to wash the

sand, &c., down the same into a tank, F, which is provided with a screen, F', to prevent pebbles or pieces of stone from being washed into the tank. The inclined platform D is also inclined downward from both sides to form a groove, D², along the middle of which groove the pipe E, provided with the spouts E', is located.

In the tank or box F a wheel, G, is arranged, over which a bucket-chain, H, passes, which also passes over a wheel, I, located above the wheel G.

A short distance below the upper wheel, I, one end of a gutter, J, is arranged, which extends down to a point over the block of stone C, and conducts the sand and water upon the inclined or swing boards K, from which they drop upon the block of stone. The mixture of sand and water is dumped from the buckets L of the bucket-chain H into the trough or gutter J.

For the purpose of washing out all the particles of sand in the buckets, I have provided a pipe, M, which has its lower end bent to form a nozzle, M', adapted to deliver water into the buckets as they turn over the pulley or wheel I. The pipe M extends downward from a tank, N, on top of which a screen, O, is arranged, which is provided at one end with an overflow, O'. Water is delivered by a pump through a pipe, P, upon the screen O, passes through the same, through the pipe M, and through the nozzle M'. The screen O prevents sawdust or any foreign substance that might be pumped up with the water, and that would clog the pipes, from passing into the tank N. All such foreign substances are carried over the screen by the force of the water and discharged from the nozzle or spout O', whereby the screen is cleaned automatically, and can never be clogged. Each bucket L of the bucket-chain is provided at its upper end with a hook-lug, L', which is adapted to pass through a transverse slot, L², in the bottom of the next higher bucket, and thus, by hooking the buckets together, an endless bucket-chain is formed. The buckets are made of cast-iron, and their cavities must be so shaped that they can easily discharge the sand and water at the wheel I.

Instead of making the buckets in the manner described, they can be provided with jaws 77 at the top and bottom, the bottom jaws be-

ing united by a bolt, *m*, and the upper jaws by a tube, *n*. The width of the bucket *L* decreases from the bottom to the top, so that the upper end of one bucket can be passed in between the lower jaws of the next higher bucket, the bolt *m* being then passed through the lower jaws of the upper bucket, the upper jaws of the lower bucket, and through the tube *n* of the lower bucket, the buckets being thus united to form a chain. By having the buckets constructed in this manner the tube *n* and the bolt *m* can easily be replaced by others in case they are worn out.

My improved faucet (shown in Figs. 8 and 15 9) consists of a tube, *S*, having its open end curved downward, and provided with a laterally-projecting wing, *S'*, to which a gate, *T*, having a suitable handle, is pivoted. In the bottom of the gate a notch, *W*, is formed. By 20 having the bottom of the gate cut out in this manner all the sand, gravel, &c., in the faucet are washed out every time the faucet is opened, even if it is opened but a very short distance.

The operation is as follows: A quantity of 25 fresh sharp sand and water is placed in the tank *F*, and raised from the same by means of the bucket-chain *H* to the gutter *J*, in one end of which it is deposited. It runs down the said gutter upon the inclined or swing boards *K*, and 30 drops from the same upon the block of stone, thus coming in contact with the saws and doing the sawing. It then runs down the inclined platform *D'* back into the tank *F*. The tank *F* is provided with an overflow-pipe, *F'*, through 35 which the waste sand and water flow off—that is, the sand that has lost all its cutting properties and, being lighter, is held in the water, while the heavier sand settles.

In place of providing the overflow-tank *F* 40 below the bucket-chain, it can also be arranged at the upper end of the bucket-chain, as shown in dotted lines at *R* in Fig. 1. The sand and water are conducted from the said tank at or near its bottom through the gutter *J* to the 45 inclined or swing boards *K*, and the waste sand and water overflow from the tank *R* through a suitable pipe or nozzle at or near the top of the said tank. Fresh sand is to be filled into the tank *F* at suitable intervals, to 50 replace the sand that has been worn out in the process of sawing and washed off with the waste water.

Having thus fully described my invention, I 55 claim as new and desire to secure by Letters Patent—

1. In a stone-sawing machine, the combination, with the water-pipe, of the tank having a screen in its upper part and an overflow-spout discharging above and at one side of said screen, said tank having a pipe connecting with its bottom and ejecting water into the relatively upper buckets of a chain or series of buckets whose relatively lower buckets are disposed in a return water and sand tank, said buckets discharging into a gutter with its lower end overhanging the saw-frame, substantially as and for the purpose set forth.

2. In a stone-sawing machine, the combination, with the water-pipe, of the tank into which it empties, said tank having a pipe 70 connecting with its bottom and provided with a nozzle ejecting water into the relatively upper buckets of a series or chain of buckets whose relatively lower buckets are disposed in a return water and sand tank, said buckets 75 discharging into a gutter with its lower end emptying into a trough leading to said latter tank, substantially as and for the purpose set forth.

3. In a stone-sawing machine, the combination, with the water-pipe, of the tank having a pipe connected to its bottom and ejecting water into the relatively upper buckets of a chain or series of buckets whose relatively lower buckets are disposed in a return water 85 and sand tank, said buckets discharging into a gutter with its lower end overhanging a trough leading to the return water and sand tank, said latter tank having a tube provided with a gate having a notch in its bottom edge, 90 substantially as and for the purpose set forth.

4. In a stone-sawing machine, the chain or series of buckets having prongs or jaws at their upper and lower ends, a tube being held transversely in the upper prongs or jaws and a pin 95 or bolt in the lower prongs or jaws, the upper end of one bucket being passed between the prongs or jaws of the next higher bucket, and the bolt of the upper bucket being passed through the tube of the lower bucket, in combination with the supply-tank having connection with said buckets by a pipe, said buckets 100 discharging into a gutter overhanging the saw-frame, substantially as and for the purpose set forth.

5. In a stone-sawing machine, the water-tank having a screen in its upper part and an overflow-pipe above said screen, said tank also having a nozzled pipe, in combination with the chain of buckets juxtaposed to the 110 said nozzled pipe, and with its relatively lower buckets disposed in a return water and sand tank and its relatively upper buckets discharging into the gutter, said gutter having its lower end discharging upon inclined 115 swing-boards overhanging the saw-frame, the double inclined platform having a central inclined groove or trough emptying into said return water and sand tank, substantially as and for the purpose set forth.

6. In a stone-sawing machine, the water-tank having a screen in its upper part and an overflow-pipe above said screen, said tank also having a nozzled pipe, in combination with the chain of buckets juxtaposed to the 125 said nozzled pipe, and with its relatively lower buckets disposed in a return water and sand tank and its relatively upper buckets discharging into a gutter, the lower end of said gutter discharging upon inclined swing-boards overhanging the saw-frame, the double inclined platform having a central inclined 130 trough or groove emptying into said return sand and water tank having a screen and over-

flow-pipe, substantially as and for the purpose set forth.

7. In a stone-sawing machine, the water-tank having a screen in its upper part and an overflow-pipe above said screen, said tank also having a nozzled pipe, in combination with the chain of buckets juxtaposed to the said nozzled pipe, and with its relatively lower buckets disposed in a return water and sand tank and its relatively upper buckets discharging upon inclined swing-boards over-

hanging the saw-frame, the double inclined platform having a central inclined trough or groove emptying into said return sand and water tank having a screen and overflow-pipe, and the pipe having branch pipes and arranged upon the said inclined platform, substantially as and for the purpose set forth. 15
